UNITED STATES PATENT OFFICE.

HANS PETER DINESEN, OF HERLÖV, DENMARK.

METHOD AND APPARATUS FOR DRYING MATERIALS IN SACKS AND THE LIKE.

1,271,293.

Specification of Letters Patent.

Patented July 2, 1918.

Application filed January 25, 1916. Serial No. 74,224.

To all whom it may concern:

Be it known that I, HANS PETER DINESEN, engineer, of Herlöv, in the Kingdom of Denmark, have invented certain new and useful Improvements in or Relating to a Method and Apparatus for Drying Materials in Sacks and the like, of which the following is a specification.

The present invention relates to a method for drying materials in sacks and apparatus to be used by the application of the method. The invention aims chiefly at obtaining a cheap and good drying of corn, seed and other agricultural produce at the place of origin; so that the great losses by conveying and storing moist corn and seed are avoided. The invention may however be applied for drying all sorts of granular, gritty, fibrous or knotty materials which may be contained in sacks or similar porous vessels.

In the accompanying drawing—

Figure 1 shows a cross section of a drying apparatus with a sack of material to be dried,

Fig. 2 shows a drying apparatus without sacks in a front view,

Fig. 3 shows a cross section through a modified form drying apparatus,

Fig. 4 shows a cross section of another modification of the drying apparatus for two rows of sacks,

Figs. 5, 6 and 7 show an additional modification of a drying apparatus in cross section, plan and longitudinal section together with several details of construction,

Figs. 8 and 9 are cross sections through modifications of my apparatus with special arrangements.

In Fig. 1 the number 1 designates a sack containing the material which is to be dried, and 2 an air-shaft of triangular or square cross section. One of the walls of the air-shaft consists of a traverse plank 3 above and a similar thicker plank or beam 7 below. Between these planks are arranged cross-pieces 4, 5 and 6 which at the top rest upon the plank 3 and below meet the plank 7 and rest upon this or upon a special plank 22.

The cross-pieces 4, 5 and 6 are given a shape, so that they together with the planks 3 and 7 make frames around holes 8 in the wall of the air-shaft. 9 is the side-wall of the air-shaft and 10 the bottom of the shaft, which rests upon beams 11 and simultaneously may form the floor of the drying room,

12 and 13 are pieces which fill in the corners between the cross-pieces 5, 6 and the plank 7, 14 being pieces which fill in the corners between the cross-pieces 5, 6 and the plank 3. The parts 3, 5, 6, 7 and 12, 13, 14 are adjusted so that they form a support for the sack and fit to its shape. 15 (Fig. 2) is an air-pipe which is connected with a transportable apparatus for supplying or removing air, and 16 is a valve for regulating or cutting off the air.

The drying is executed in the following manner.

Sacks containing materials to be dried are placed over all the holes in the air-shaft, so that each of the sacks rests upon and by its own weight everywhere fits tightly to the border of the hole 8. Thereby the sacks with their contents together with the pieces 3, 4, 5, 6, 7 and 12, 13, 14 will form a partition between the chamber in the shaft 2 and the outer air, by which the shaft-pieces are impenetrable, while the sacks with their contents form a porous part of the partition. A difference of pressure at the two sides of the partition is now produced with the result that the air flows from the chamber with the higher pressure through the sacks with the materials to be dried to the chamber with the lower pressure and thereby removes moisture from the material to be dried. To accelerate the drying action heated air may be used in the shaft 2 or in the space on the opposite side of the bags, according to the relative pressure on said sides, it being desired that the hot air should be drawn or forced through the bags and their contents. As the air may obviously be derived from any source of hot air supply or be heated on the spot, it is unnecessary to illustrate any especial heating device.

The instalment may be very simply constructed in such a manner that an ordinary stove heats the air in the chamber where the drying-apparatus is placed, the pipe 15 being connected with the chimney or in bigger instalment—with an ejector or other suitable apparatus by means of which the air is forced to flow from the outside through the sacks with their contents into the shaft 2 and is removed from the latter. The instalment may also be constructed in such a manner, that the air is heated in a special heating apparatus and by means of a blower or the like is pressed into the shaft 2 from 110

which it flows out in the outer air through the sacks with their contents. The last method must as a rule be preferred by all bigger instalments, as hereby loss of heat 5 through the walls of the chamber is prevented.

In Fig. 3 is illustrated a drying apparatus with a number of sacks arranged above a common, big opening. The sacks are arranged 10 in such a manner that they together cover the opening completely; and the drying takes place in the above described manner.

In Fig. 4 is illustrated a drying apparatus 15 for two rows of sacks, having the arrangement that the air-pipe 15, which at the top is closed by a carrying plank 17, is introduced between the rows of sacks and by means of openings with flap-valves 19 connected 20 with a shaft 2 in front of each sack, the valves 19 turning around pins 20 and being provided with projections 21. The sack being put down presses against the projection 21 and opens the valve 19 whereby 25 the air can pass through the sacks. As the latter may be of different size and density and therefore may offer a somewhat different opposition to the passage of the air, the holes 18 may have different sizes or the 30 valve 19 fit to variable openings, and the biggest and most tight sacks may be arranged in front of the holes with the biggest opening. The apparatus shown in Figs. 1-3 may of course be executed double as 35 shown in Fig. 4, and the arrangement illustrated in this figure can also be applied by Figs. 1-3.

The above described apparatus are especially to be applied for drying materials 40 with small friction, permitting the sack to alter its shape considerably in the apparatus. When used with wet materials and materials of great friction the sack will only close with a narrow edge of the frame, and 45 in these places the air therefore will only have quite a short way to pass through the material to be dried. To make the supporting flats broader and fashion them completely after the sack makes the apparatus 50 rather costly and is not quite satisfactory, especially when the sacks are of different size.

This drawback is removed by the apparatus shown in Figs. 5-7, in which the sides 55 and the top of the frame are provided with double edges, so that the sack will rest upon two frames, one outside of the other. Thus the beam 3 is provided with two pieces 14 which form the support of the sack. The 60 cross-pieces 5 and 6 are provided with lists 24, so that the sack at the sides will rest upon four parallel edges 25. Between the cross-pieces 5, 6 and the lists 24 are inserted small pieces 26.

It will easily be seen from Fig. 7 that the

air has a much longer way to pass through the material to be dried along the supporting flat than when the sack only closes against one single edge.

For materials of great friction and for 70 sacks of different sizes a similar effect may be obtained by making the cross-piece 6 movable laterally. The cross-piece can either be adjusted after the size of the sack and fastened or be wedged under the sack 75 after the placing of the latter. On the movable cross-piece is fastened a part of the piece 14 and in some cases also the lower piece 13.

By the apparatus shown in Figs. 5-7 the 80 frame may be adjustable thereby that the cross-piece 6 with the list 24 and the pieces 26 and 13 is movable laterally. The joint between the concurrent cross-pieces 6 (Figs. 85 6-7) is covered by a plate 29, and the cross-pieces may be kept in position by means of spacing pieces 30. Instead of moving the cross-piece 6 the lists 24 and the pieces 26 may also be adjusted and kept in position by means of spacing pieces 30. Thereby the 90 whole inner frame with the pieces 12 and 13 will be stationary and only one or both lateral parts of the outer frame will be movable.

Finally the apparatus may be adjusted 95 for sacks of different length, the top plank 3 which carries the lists 14 being movable in the longitudinal direction of the sacks and adjustable in different positions, as a list 28 on the plank 3 rests upon fixed lists 100 27 which are arranged upon a beam, the latter being fastened to the wall 9 of the shaft.

The air-shaft 2 in most cases has the shape shown in the drawing, the flat carrying the sacks sloping at an angle of 0° - 75° , preferably between 30° and 60° with a horizontal plane, and the lower frame-piece 7 being placed near the floor. This construction is both good and cheap and specially adapted 110 for conveying the drying material by sack-car.

In Figs. 8-9 are shown two modifications of an arrangement which is placed upon the drying apparatus and by means of which the latter also may be applied for the drying 115 of substances which can not be put into sacks or the like vessels.

In Fig. 8 a grate 31 carrying the material 120 to be dried is placed above the sacks 1. The grate 31 is fastened by means of hinges 33 to the lengthened back 9 and has such a shape that a closed chamber 34 is created above the sacks, the chamber 34 being only by means of the openings in the grate 31 connected with the outer air. During the 125 drying process the air penetrates into the shaft 2, passes through the sacks 1 to chamber 34 and from here through the openings in the grate 31 and upward through the material to be dried 32. The drying air 130

thus will be used twice, whereby the thermic effect of the apparatus is heightened. When the sacks 1 are to be changed the grate 31 is pushed upward, the same turning around 5 its hinges 33.

In Fig. 9 the grate 31 is arranged resting upon the borders 24 which surround the sacks. When the grate is not in use, it is turned upward around hinges as in Fig. 8 10 or completely removed.

Having now described and ascertained the nature of my said invention I declare that what I claim is:

1. In combination with the walls of an air 15 space normally left open on one side, a frame occupying this side and provided with openings adapted to be filled by sacks of material in order that the sacks may constitute the greater part of a wall of said 20 space, compelling air to pass through them when a difference of air pressure is established between said space and the opposite side of said sacks.
2. In combination with the walls of an air 25 space which has an obliquely arranged open side, an inclined frame fitting said side and provided with an opening or openings adapted to be filled by bags of material resting in said frame in inclined position, in 30 order that air may pass through said bags into or out of said space for drying such material.
3. In combination with the walls of an air 35 space, an inclined frame provided with one or more openings and adapted to support one or more filled bags of material in inclined position, completing one side of said

space but permitting air to pass through said bags, the said frame being provided with a double border surrounding each opening partly or wholly, for the better support 40 of said bags.

4. In combination with the walls of an air space, an inclined frame for holding one or more bags of material in inclined position 45 completing one side of said space and permitting air to pass through said bags, the said frame being provided with parts adjustable longitudinally of the bags.

5. In combination with the walls of an air 50 space, an inclined frame for holding one or more bags of material in inclined position, completing one side of said space and permitting air to pass through said bags, the said frame being provided with parts adjustable laterally of the bags.

6. An apparatus of the character described comprising a support having openings therein, said support adapted to receive sacks containing material which is to be 60 dried and the said sacks adapted to rest over said openings, and means for supplying air to (or withdrawing air from) the said support whereby the air will pass through the sacks with the material to be dried as set 65 forth.

In testimony whereof, I have signed my name to this specification in the presence of two subscribing witnesses.

HANS PETER DINESEN.
